MENDEL OSNOS, OF BERLIN, GERMANY, ASSIGNEE TO GESELLSCHAFT FÜR DRAHTLOSE TELEGRAPHIE M. B. H., OF BERLIN, GERMANY, A CORPORATION OF GERMANY

RADIO SYSTEM

Application filed January 25, 1926, Serial No. 83,452, and in Germany March 12, 1925.

The present invention relates to telephony arrangements of the kind wherein an audio transformer primary is fed from a microphone or an amplifier unit and is based upon 5 the idea that the audio transformer is liable to constitute a source of harmful influences tending to impair faithful reproduction of the timbre. Such distortions of the timbre are ascribable or traceable to the iron saturation 10 of the transformer by the "idle" current of the microphone or of the amplifier.

According to this invention, this inconvenience is obviated by supplying the secondary of the transformer with a direct current 15 which wholly or partly neutralizes the saturation produced in the primary by the idle current.

A number of embodiments of the idea underlying the invention are diagrammatically 20 shown in the drawing, in which:—

Fig. 1 shows a diagrammatic sketch of one embodiment of this invention.

Fig. 2 shows a slightly different modified form.

25 Fig. 3 shows a variation of Fig. 2.

Fig. 3^a shows still another variation.

Fig. 3^b shows another variation.

In Fig. 1 is shown the well known telephony arrangement for high frequency installations (disclosed in German Patent No. 300,171), wherein a telephony iron-cored choke coil (magnetic modulator), provided with a winding *w* for high frequency power current and windings *g*¹ and *g*² for superposed direct current or microphone (telephony) current, receives the latter from a speech or audio transformer *ps* whose primary is excited by a microphone. *b*¹ is a battery furnishing both the idle current of 40 the microphone as well as the idle current of winding *g*¹. The resistances *r*¹ and *r*² serve for providing adjustment of the two currents independently of one another. Condensers *c* are the shorting condensers serving to choke off currents of higher frequencies. The primary winding *p* of the audio transformer carries both the speech current of the microphone as well as its idle (closed-circuit) current. Now, in conformity with 45 the invention the saturation caused by the

said idle current is neutralized by connecting a direct current source *b*² with the secondary of the audio transformer, a variable resistance *r* and protective choker *d* being inserted in the leads. By suitably adjusting the resistance *r*, it is possible to substantially neutralize the idle current of the microphone by the direct current furnished by *b*². 55

In Fig. 2 is shown an arrangement resembling Fig. 1 except in this case, the audio transformer *ps* receives the speech current from an amplifier arrangement *v* subject to microphone modulation by telephone *t*. The modulation choker *T* may here consist, for instance, of a conductor provided with an iron coat or cover. Its middle point *a*¹ serves as one of the current-supply terminals for the high frequency alternating current to be controlled or modulated, while the middle point *a*² of condensers *c* joining its two ends *k*¹, *k*² constitutes the other terminal. The superposed direct current (idle current) is supplied at the terminals *k*¹, *k*² from the battery *b* through resistance *r*² and choke coils *d*; in parallel relationship thereto is provided the secondary winding *s* of the audio transformer. By the aid of a resistance *r*¹ connected, for instance, in parallel with condenser *c*¹ it is possible to adjust in the secondary winding *s* of the audio transformer 80 the requisite direct current or ampere turns furnished by the battery *b* in order to neutralize the saturation caused by the idle current. 75

If in this arrangement it is preferred to place the winding *s* of the audio transformer not in parallel, but in series with the direct current source, then, for the purpose of adjustment of the necessary direct current or ampere turns it is necessary to dispose a regulating circuit *dr* (Fig. 3) or one regulating circuit in each case, either in parallel with the telephony choker or with the winding *s* (Fig. 3^a), or with relation to both of these (Fig. 3^b). 90

It is obvious that the principle above described may be applied to balance out saturation caused by idle currents either in the primary or secondary of any transformer. 95 100

Having thus described my invention, what I claim is:—

1. In a radio system, a transformer consisting of a primary, a secondary and a core, a source of input current to the primary of said transformer and means connected to the secondary of said transformer adapted to substantially neutralize the saturation of said transformer produced by the input current. 5
2. In a radio system, a transformer consisting of a primary, a secondary and a core, a source of input current to the primary of said transformer and means connected to the secondary of said transformer adapted to substantially neutralize the saturation of said 10 transformer produced by the input current, said latter means consisting of a source of direct current fed to said secondary.
3. In a radio system, a transformer consisting of a primary, a secondary and a core, a source of input current to the primary of said transformer and means connected to the secondary of said transformer adapted to substantially neutralize the saturation of said 15 transformer produced by the input current, said latter means consisting of a source of direct current fed to said secondary, said input current and the said direct current sources being connected in parallel.
4. In a radio system, a transformer consisting of a primary, a secondary and a core, a source of input current to the primary of said transformer and means connected to the secondary of said transformer adapted to substantially neutralize the saturation of said 20 transformer produced by the input current, said latter means consisting of a source of direct current fed to said secondary, said input current and the said direct current sources being connected in parallel and regulating 25 means for regulating said currents.
5. Telephony arrangement comprising a speech transformer with a primary supplied from a microphone or amplifier, characterized by that the saturation of the speech 30 transformer produced by the primary ampere turns of the idle current of the microphone or amplifier, is neutralized wholly or partly by means of a direct current fed to the secondary of the speech transformer.
6. In a transformer having a primary winding, a secondary winding, and a magnetic core, modulating means in circuit with the primary coil having an idle current flowing therein, means comprising a circuit having a choke coil and a direct current source in parallel with the said secondary winding whereby magnetization of the core due to the 35 said idle current of the primary winding is partially neutralized.
7. In a transformer having a primary winding, a secondary winding, and a magnetic core, a variable resistance in series with said secondary winding and a condenser in 40 parallel with said resistance, modulating 45

means in circuit with said primary coil having an idle current flowing therein, means comprising a direct current source in said secondary circuit whereby magnetization due to said idle current in said primary winding is at least partially neutralized. 70

8. In a transformer having a primary winding, a secondary winding, and a magnetic core, modulating means having an idle current flowing therein, a direct current source in series with said secondary winding, and means comprising a variable resistance in series with a telephone choke coil, in parallel with said secondary winding for at least 75 partially neutralizing the magnetization due to the idle current flowing through said primary winding circuit. 80
